UNITED STATES PATENT OFFICE.

HARRY ROBERT NORTHOVER, OF WINNIPEG, MANITOBA, CANADA.

MACHINE FOR FILLING THE MAGAZINES OF MACHINE-GUNS.

1,313,727.

Specification of Letters Patent.

Patented Aug. 19, 1919.

Application filed June 25, 1917. Serial No. 176,863.

To all whom it may concern:

Be it known that I, HARRY ROBERT NORTHOVER, subject of the King of Great Britain, residing at Graham avenue, Winnipeg, Manitoba, in the Dominion of Canada, gunsmith, have invented certain new and useful Improvements in Machines for Filling the Magazines of Machine-Guns, of which the following is a specification.

10 This invention has reference to that type of machines for filling Lewis-gun magazines which embody a magazine-support adapted to lock the magazine center-block in a position wherein the entrance to the groove in the 15 said center registers with the outlet from a cartridge hopper, and manually-operated mechanism which alternately feeds a cartridge into the magazine and feeds or rotates the pan of the said magazine to bring 20 the space for the reception of the next cartridge into register with the hopper outlet. A magazine-filling machine of the above 25 mentioned type is described in the specification of British Patent No. 15,220 of 1915. In this, it is proposed to effect both the feeding 30 of the cartridges into the magazine and the rotary feed of the magazine pan by a conical sprocket toothed roller that is rotatably mounted in a body part which is 35 mounted by a cartridge-hopper and has the cartridge outlet on its underside; the magazine support being also disposed on the underside of the said body and below the sprocket feed device. In this arrangement, 40 the feed or delivery of the cartridges from the hopper into the magazine is effected by the sprocket device assisted by gravity or by the weight of the cartridges, while the magazine feed is performed by the sprocket teeth 45 engaging with previously inserted cartridges in the magazine. That is to say, each cartridge, after being inserted into a rim recess and between separator pegs of the magazine, serves as the medium where through the next 50 feed or step-round motion is transmitted to the pan, so that in the event of the sprocket mis-feeding the pan is not rotated and thus "blanks" in filling are avoided.

In the improved machine which constitutes 55 the present invention, the alternating operations of feeding in a cartridge and rotating or feeding round the magazine-pan are effected by independently-acting devices both driven from a common operating mechanism. The cartridge-feed device is positive in action (*i. e.*, in no way dependent on

the assistance of gravity) and is adapted to thrust or force cartridges sidewise into a magazine that is supported on the machine in a plane perpendicular to the hopper outlet, and the pan-feed device operates by directly engaging the pan itself, thus avoiding the undesirable use of cartridges as a pan rotating medium, while "blanks" in filling are rendered impossible by an automatic 60 stop-mechanism which controls both the cartridge and pan-feeds and will not allow the pan to be rotated or fed round, except after the cartridge feed has operated to properly introduce a cartridge into the magazine. 65

In the preferred embodiment of the invention, the positively-acting cartridge-feed device consists of a reciprocating plunger working in a plane at right angles to the plane in which the magazine is supported on 70 the machine, and the magazine feed device consists of a pawl or the like adapted to engage with the recesses that are formed in the periphery of the Lewis magazine to provide engagements for the feed and stop 75 pawls of the gun. Both the cartridge and pan-feed devices are driven, from the same crank-handle, hand-wheel, or the like, through gearing which is so arranged that the pan-feed pawl operates to give the feed 80 movement to the pan during the return or idle stroke of the cartridge-feed plunger, whereas during the working or feeding stroke of the said plunger, the pan-feed pawl makes an idle return motion; the pan being 85 meanwhile held fast by a steady or stop pawl that also engages the peripheral recesses of the magazine. The stop mechanism which prevents the occurrence of "blanks" is directly controlled by the weight of the cartridges in the hopper of the cartridge-feed 90 system, and is adapted to stop the working of the machine by arresting the cartridge-feed plunger in the event of a cartridge failing to fall, at the correct time, into the path 95 of the said plunger and into register with the hopper outlet. Further, the invention embodies several other special features as 100 hereinafter described and claimed with reference to the accompanying drawings, which render the machine capable of rapid working and certain in action, and counteract or deal with all disturbing contingencies that can possibly occur in the mechanical filling 105 of a Lewis magazine.

In order that the principles on which the improved machine operates may be better

understood I have shown in Figure 1 and in Fig. 2 of the drawings, a transverse section and a quarter horizontal section of a Lewis magazine of the 47-round pattern, while Fig. 3 is an elevation of the face of the center block and the spacing ring surrounding same; these views illustrating the formation of certain parts of the said magazine that are made use of, when the pan is being filled by my machine, for assisting the proper disposition of the cartridges in layers in the said pan. This magazine comprises a circular pan a whose rim is formed with external depressions a^2 and internal recesses a^3 which latter receive the base of the cartridges whose rims are engaged by the retaining plates a^4 , while the inside of the top of the pan is furnished with a spacing ring a^5 carrying the separator pins a^6 that cooperate with the recesses a^3 and plates a^4 to keep the radially-disposed cartridges in their correct positions. The pan a is rotatably mounted on the magazine center-block, b ; said pan and center being secured together, when detached from a gun, by a catch; but when the magazine is on the magazine-post of the gun (and also when mounted on the filling machine hereinafter described) the catch is displaced and leaves the pan free to be rotated around said center-block.

In the periphery of the center-block are two grooves b^2 , b^3 , to take the bullet ends of the two layers of cartridges; the groove b^2 merging, by an inclined "lip" b^4 into the opening b^6 wherethrough cartridges are delivered into the gun, while the two grooves communicate with one another by an inclined channel b^5 , which is arranged above, and has the same pitch, as, the incline, b^4 , and provides for the transfer of cartridges from the plane of the groove b^3 into the plane of the groove b^2 as the pan is intermittently rotated by the feed-pawl of the gun. But when being filled by the machine and the pan is rotated in the reverse direction to that in which it is turned on the gun, the incline b^4 directs the bullet ends of the fed-in cartridges into the said groove b^2 , while the channel b^5 directs the cartridges from the said groove b^2 into the groove b^3 after the said pan has been turned through about one complete revolution; it being understood that to fill a two-layer or 47-round magazine, the pan has to be turned through approximately two revolutions, during the first of which, said pan receives a layer of cartridges that lie in the plane of the groove, b^2 , with which their bullet ends engage, while during the rest of the pan movement, these cartridges from the above mentioned layer are transferred from the plane of the groove, b^2 , into the plane of the groove b^3 and their places in said groove b^2 are taken by further cartridges from the

machine until both layers are complete. Further, as each individual cartridge is delivered from the machine into the magazine, its bullet end passes through the opening b^6 and comes onto the incline b^4 , its neck is engaged between a pair of the separator pins a^6 and its base is passed into the corresponding recesses a^3 and is engaged by the retaining plates a^4 of that recess. Each cartridge is thus positioned in radial relationship to the center-block and is compelled to move with the pan during its rotation around the said center-block.

Proceeding now to further describe the machine with reference to the accompanying drawings,

Fig. 4 is a front elevation showing the machine mounted for use on a service ammunition box or similar support, and with a magazine in the filling position.

Fig. 5 is a plan of Fig. 6.

Fig. 6 is an elevation of the operating handle-side of the machine.

Fig. 7 shows on an enlarged scale, the front of the machine, and illustrates how the magazine-supporting post is disposed relative to the cartridge hopper.

Fig. 8 is a sectional plan (corresponding to Fig. 5 but on a larger scale) showing the general arrangement of the cartridge-feed plunger and operating mechanism.

Fig. 9 is a sectional elevation (corresponding to Fig. 6 but on a larger scale) showing the plunger in the act of transferring a cartridge from the hopper into the magazine, and also illustrating the arrangement of the automatic stop mechanism.

Figs. 10 and 11 are two detailed views of the magazine stop-pawl.

Fig. 12 is a diagram showing how the cartridges are transferred from the center-groove b^2 to the center-groove b^3 during the filling operation.

Fig. 13 is another diagram showing the position in which the magazine center-block is locked (when the magazine is mounted on the supporting post of the machine) relative to the hopper outlet.

The same letters of reference indicate corresponding parts in the several figures of the drawings.

In the machine shown, the cartridge hopper, and the whole of the working parts, are mounted on a bed plate, c , provided with claws c^2 , c^3 , and a clamping screw and nut c^4 , c^5 , whereby the said machine may be rigidly secured for use on top of a service ammunition box or the like, as shown in Fig. 4.

The hopper d and its cartridge-guide d^2 are arranged above the front of the bed-plate c and the bottom or lower part of the front of the said hopper is formed with a horizontal cartridge-outlet d^3 wherethrough the cartridges are fed sidewise into the

magazine. The magazine-supporting post *e* is located on the front of the said hopper, adjacent to the right hand or bullet end of the cartridge-outlet *d*³, as shown in Figs. 7 5 and 13; this disposition of the parts providing for the attachment of the magazine in an upright position on the front of the machine, or in a plane perpendicular to the hopper outlet.

10 The said hopper *d* is adapted to contain a pile of cartridges, and its horizontal sectional shape (see Fig. 8) is such that the cartridges can only drop into it in one way, *i. e.*, with their rims or heads to the left; the 15 rear side of its bottom being cut away at *d*^{3x} to provide working clearance for the cartridge feed-plunger, *g*, and also to admit of observation of the cartridges. To prevent cartridges rolling or dropping through the 20 outlet by gravity, and also to keep the cartridges properly superimposed, a hinged flap *d*⁵ (see Fig. 7) is arranged outside the said outlet, and is influenced by a spring *d*⁶, which yields to allow the outward movement 25 of the said flap as the bottom cartridge is thrust out of the hopper. This device prevents "double feeding" by obviating any possibility of two cartridges falling side by side in front of the plunger.

30 Above the left-hand side of the hopper is an upright channel-sectioned guide *d*², into which the rim ends of cartridges are introduced and down which the said cartridges drop, by their own weight, in correct positions into the hopper below. This guide is 35 preferably an integral extension of the detachable upper portion *d*⁸ of the hopper.

At the bottom of the hopper is a spring *d*¹⁰ (Fig. 8) which, as each cartridge drops 40 into the path of the cartridge-feed plunger, exerts an endwise thrust against the bullet end thereof and momentarily presses the cartridge to the left, thus holding the same in such a position as will insure the proper 45 engagement of its rim end with a retaining groove of the pan.

The cartridge-feed device is positive in its action and functions quite independently of any assistance from gravity or cartridge 50 weight; the same being adapted to thrust or force the horizontally-positioned cartridges sidewise from the hopper into a magazine that is supported in perpendicular relationship to the hopper outlet *d*³.

55 In the machine illustrated, the said cartridge-feed device consists of reciprocating plunger *g* which is arranged in alinement with the hopper-outlet and works between suitable guides, in a plane at right angles 60 to that in which the magazine is supported; the said plunger operating, during its outward or working stroke, positively to thrust the lowest cartridge in the hopper (which drops into the path of the said plunger 65 on the latter completing its inward or idle

stroke) through the hopper-outlet and into the magazine.

The plunger carries, above its front end, an inclined spring tongue *d*⁹ (see Fig. 9) which, during the forward or feeding stroke 70 of the said plunger, lifts all the cartridges in the hopper except the lowest one that is being transferred to the magazine. This takes the weight of the other cartridges off the said bottom one at the moment when 75 the latter is being thrust through the outlet, whereas during the return stroke of the plunger the lifting spring is withdrawn from under the column and allows the next cartridge to fall into the transferring position 80 in the path of the feed device and in register with the hopper outlet. This lifting of the cartridges by the plunger also keeps them loose or free in the hopper and so helps to avoid jams. 85

For operating the cartridge-feed plunger and the independently acting magazine-feed device, the machine is provided with a hand-actuated mechanism, comprising a crank *f* and crank plate *f*⁷ which is carried 90 on a spindle *f*², and is linked to the plunger by a connecting rod *f*³, while to prevent the machine being damaged by the continued rotation of the operating handle in the event of a jam, or after a magazine has been 95 completely filled, or if the machine is automatically stopped, there is interposed between the spindle and handle, a spring clutch whose driving element consists of two V-sectioned recesses on the crank-boss 100 *f*⁴ (the crank being loose on the spindle) while the driven portion consists of two V-sectioned projections on the collar *f*⁵ at the spindle end; the latter being adapted to engage the recesses of the crank-boss 105 which is constantly under the outward thrust of a spring *f*⁶. Normally this spring keeps the ribs of the collar *f*⁵ in engagement with the recesses of the handle and enables the crank (when rotated) to drive 110 the spindle and the cartridge and magazine-feeds so long as no abnormal resistance is offered to their movement, but if the plunger *g* should be by any means stopped and the rotation of the handle is continued, the 115 resistance to further rotation of the spindle causes the crank-recesses to disengage and ride over the projections on the spindle-collar, thus permitting the handle to rotate 120 idly and independently of the stationary spindle.

For supporting a magazine on the machine in the positions shown in Figs. 4, 5 and 6, the base carries a post, *e*, which is disposed outward of the bullet side of the 125 hopper outlet *d*³; its precise disposition being such that its center lies in the same horizontal plane as the bottom edge of the said outlet, as best seen in Fig. 7. The hole in the magazine center block is passed over 130

this post, and the said block is locked thereto, when the magazine is in position, by a key h^2 engaging in the keyway k^3 in the said center-hole; the said key being so disposed (see Figs. 7 and 13) that it will hold the magazine center block in the exact position shown in Fig. 13 in which the edge b^7 of the face opening b^6 lies horizontally and in a plane only slightly below the center of the post and the bottom edge of the hopper outlet d^2 , so that as each successive cartridge is pushed sidewise through the outlet, its bullet end will pass into the center-opening b^6 and into the contact with the inclined lip b^4 , ready to be carried into the groove b^2 by the rotation of the pan around the stationary center under the action of the magazine-feed device. It is, of course, understood that as each cartridge is passed through the hopper outlet and into the open side of the pan, its base is taken into the internal recess a^3 that is then registering with the outlet, and its rim is engaged with the retaining plates a^4 at the edges of the said recess, while simultaneously the neck of the cartridge is engaged between the corresponding pair of the separator pins, a^6 . Thus each cartridge becomes anchored in the rotatable pan while its bullet end engages the grooves in the center-block and is constrained to travel in the grooves during the rotation of the pan and cartridges around the stationary center-block.

The magazine-feed device is designed to engage directly with the external periphery of the rim of the pan for imparting an intermittent rotation to the said pan by giving the same a step-forward motion, after each insertion of a cartridge, sufficient to bring the next cartridge space into register with the hopper outlet; this rotational movement being in the counter-clockwise direction (*i. e.* in the reverse direction to that in which the pan is turned by the feed pawl of a Lewis gun) so that the various internal parts of the magazine will be caused to act in the reverse way to what they do when the pan is operated by the gun and thus they will effect or assist the proper disposal or arrangement of the cartridges within the pan instead of successively discharging them.

The said magazine-feed device is timed to operate after the insertion of a cartridge and during the return or idle stroke of the cartridge-feed device, and it consists of an oscillating arm, h , fulcrumed to stud h^2 on one side of the base and formed, at the end which projects beyond the front of the hopper, with a pawl, h^3 that engages successively with the shoulders h^4 of the external peripheral depressions a^2 of the pan, while its inner end is slotted at h^5 and is engaged by an eccentric h^6 on the operating spindle; the arrangement being such that, after the feed-

plunger has expelled a cartridge and placed it into its initial position in the magazine, the cam oscillates the lever and pawl which, during the return stroke of the said plunger, imparts a step-round motion of the said pan to bring the latter into position for taking the next cartridge. Having performed this movement, the pan is momentarily held stationary by the stop pawl i , meanwhile the feed-pawl makes an idle upward movement into engagement with the next peripheral depression a^2 and simultaneously the feed-plunger makes its next working stroke.

To admit of the easy placing and removal of the magazine on to and from the supporting post, the feed-pawl is loosely mounted on its pivot stud and is capable of a certain lateral play thereon, but when the various parts are positioned ready for filling a magazine, said feed-pawl is kept in effective contact with the periphery of the pan by the inward lateral thrust of a spring h^1 that is disposed between an elevated side of the base and the feed-lever (see Fig. 8). This spring is, however, itself controlled by the stop-pawl i in such a way that when the said stop is in its operative position, it maintains the spring under tension and compels it to exert the necessary lateral pressure for keeping the feed-pawl up to its work, whereas when the stop-pawl is manually shifted clear of the pan preparatory to removing the magazine, the tension is taken off the spring and the pressure is eased off the feed-pawl, which is then free to play about loosely on its pivot stud. That is to say, the pawl disengages itself from the pan and offers no obstruction to the removal of the magazine from the machine.

The stop-pawl spindle, i^2 has its bearing in the side of the base, and carries, at its extreme forward end, a catch arm i^3 that is adapted to be turned over the outer edge of the pan, (see Fig. 8) for steadyng the latter during its rotary movement, and is combined with a finger-piece i^4 by the turning of which in an appropriate direction, both the stop-pawl and the pan-catch can be taken into or out of their effective positions. Fig. 8 shows the positions assumed by the stop-pawl and catch when a magazine is being filled, while the detail views, Figs. 10 and 11, show the positions into which the said parts are shifted prior to the removal of the magazine.

When the machine is operating, the stop-pawl is yieldingly held in engagement with the pan periphery by a spring m^5 which bears eccentrically underneath a corner of a hub m^6 of the stop-pawl arm; this arrangement admitting of the pawl yielding outward sufficient to allow of the recessed periphery of the pan wiping under its nose each time that the said pan is driven around a step by the magazine feed-pawl.

The stop-pawl hub is adapted to function

as a cam for controlling the feed-pawl spring h^1 , for which purpose, its edge is formed with two flats m^7 , m^8 , (best seen in Fig. 10) that are disposed at an angle to one another but at different distances from the center of the pawl spindle. The free end of the spring bears against the pawl hub as shown in Figs. 10 and 11, and the arrangement of the flats is such that, when the stop-pawl is turned outward into its inoperative position, the flat m^7 nearest the spindle center comes behind the spring and relieves the latter of its tension so that the feed-pawl is free to play laterally as clearly seen in Fig. 11, whereas when the stop-pawl is turned inward, the other flat m^8 of the cam bears on the spring, and (by reason of its greater distance from the pivot center) presses the spring inward and maintains it in that position, in which it bears effectively against the feed-pawl for keeping the latter up to its engagement with the pan.

To enable the machine to accommodate the magazines of Lewis guns of either the field-service pattern (47 rounds) or of the aeroplane type (97-rounds), the catch i^3 and the stop-pawl i are adjustably mounted on the frame so that their distance from the face of hopper may be varied to suit the depth of the magazine to be filled. That is to say, the said parts i^3 , i are mounted on a sliding rod or spindle i^2 (see Fig. 8) and this spindle is formed with two grooves i^5 , i^6 , with one or other of which, a suitably applied retaining spring is adapted to engage, according to the position in which the said spindle is placed. Thus, after the spindle has been drawn out or adjusted to suit the kind of magazine to be filled, it is automatically locked and the catch and stop-pawl are secured in the right positions until another alteration is necessary. The magazine-supporting post is slidably mounted in the machine and is capable of a corresponding adjustment; the same being provided with a set-screw for locking it in either position.

The automatic stop mechanism embodied in this machine is of the kind wherein the stop-feed device is held out of action so long as the machine functions normally and so long as cartridges continue to successively position themselves in the path of the cartridge-feed device, but which comes into operation to arrest the working of the said machine in the event of a cartridge or cartridges failing to be so positioned. And this stop mechanism and the means whereby the same is controlled are so constructed, arranged, and timed to operate that the stopping of the working can only occur at one particular point in the cartridge and pan feeding cycle, viz. at the instant when the pan-feed device has completed the movement

that brings an empty space in the magazine into register with the hopper outlet, and the cartridge feed device is about to commence its next working or feeding operation. The object of this timing of the stop action is to insure that, when the said stop device is disengaged to allow the machine to resume working, all the parts are correctly positioned for effecting the feed of a cartridge into the said empty space in the magazine.

The stop-mechanism embodied in the present machine is best shown in Fig. 9, of the drawings, and is carried on the underside of a bracket-plate j^2 , which is supported upon the bedplate c and over which the cartridge-feed plunger g reciprocates. It comprises a system of counterweighted levers, viz. a control lever j^3 and a plunger-stop lever j^4 , and the lever j^3 which in practice consists of a pair of separated but rigidly connected side-plates, and is pivotally hung from a forked bracket attached to the underside of the plate j^2 ; the end farthest from the hopper carrying a counterweight, j^5 , while its hopper end is furnished with a cartridge contact piece j^6 that is located in the said plate j^2 immediately below the open bottom of the hopper. This arrangement provides that as each successive cartridge drops from the hopper into its feed position between the hopper-outlet and the plunger, it rests upon the contact j^6 .

The plunger-stop lever j^4 is located between the side plates of the control lever, and is independently pivoted on a hanger j^8 inward of the control-lever bracket. Its rear extremity is loosely pivoted at j^9 to the counterweight end of the control lever while its forward part carries a plunger-stop j^{20} disposed (as shown in Fig. 9) in another opening j^{22} that is formed in the bracket-plate j^2 , at some distance inward of the cartridge contact j^6 .

The distance between the centers of the cartridge contact j^6 and the plunger-stop j^{20} is less than the length of the stroke of the plunger, and the relative dispositions of the parts g , j^6 , j^{20} , are such that, during the greater portion of its reciprocation, the said plunger is riding either over the contact j^6 and the stop j^{20} or over the stop only, and this renders it impossible for j^6 or j^{20} to be lifted or made to project above the top surface of the plate j^2 by the action of the counterweight on the two levers, but as the plunger comes to the end of its idle or return stroke, it is quite clear of the plunger-stop, j^{20} , with the result that the stop mechanism is freed of the restraint previously exerted thereon by the plunger. The movement of the plunger beyond the stop, j^{20} coincides with the completion of a feed movement of the magazine pan under the action of the pan-feed device, h and provided that, at this moment, there are cartridges in the hopper

ready to fall the bottom cartridge drops into the feed position on top of the control lever contact j^6 , when the weight of the cartridges bearing on said contact will counteract the 5 tendency of the counterweight to lift the plunger-stop and the continued rotation of the operating crank will impart the working or feeding stroke to the plunger and the said bottom cartridge will be fed or thrust into 10 the magazine space that is in register with the hopper-outlet. And as the plunger advances it rides first over the stop j^{20} and then over the contact j^6 so that before the cartridge weight is taken off the control 15 lever by the feeding and cartridge lifting action of the parts g , d^9 , the stop mechanism is already under the restraint of the over-riding plunger and so cannot possibly operate to arrest the working of the machine. 20 If, however, at the moment when the plunger slides clear of the stop, j^{20} , there is not sufficient weight of cartridges ready to fall onto the control lever contact and overcome the counterweight, then the said counterweight immediately takes control and by 25 oscillating the levers j^3 , j^4 , lifts the stop j^{20} into the path of the plunger and also causes the cartridge contact to project above the surface of the bracket-plate j^2 . This renders it impossible for the continued rotation 30 of the driving crank to impart a useless or non-effective forward movement to the plunger, and as the pan-feed device is geared to, or worked from the same operating device 35 as the said plunger, it follows that the locking or arresting of the plunger simultaneously and positively locks the pan-feed device and thus prevents any movement being imparted to the pan which would result in a 40 "blank" space in the magazine.

The stop mechanism automatically liberates or releases the cartridge-feed and pan feed devices immediately a sufficient weight of cartridges falls onto the control lever contact j^6 to overcome the counterweight, when 45 the resultant oscillation of the levers removes the plunger-stop j^{20} from the path of the plunger and leaves the said feed-devices free to carry on their respective functions 50 on rotation of the operating handle being resumed.

After an empty magazine has been placed on the supporting post, and the operating crank is turned to start the filling action 55 about the first twenty-three rotations of the crank cause the said pan to turn through one complete rotation and effect the transposition from the machine into the magazine of a sufficient number of cartridges to make up 60 a complete layer or annular series of cartridges in the open side of the said pan, nearest the hopper. During the next rotation of the pan, the cartridges from the first layer have to be transposed or shifted over 65 to the closed side of the pan to make room

for the remainder of the prescribed number of cartridges required to complete the filling. The transposition is effected by the pan, during its counter-clockwise motion around the stationary magazine center block 70 compelling the bullet ends of the first-inserted series of cartridges to travel out of one center-block groove b^2 down the inclined channel b^5 into the other groove b^3 .

To assist this action of the magazine parts, 75 the machine itself is provided with means whereby these cartridges are subjected to pressure as their bullet ends are brought (by the rotation of the pan) into the inclined transposing part b^5 of the center block 80 grooves. For this purpose, there is formed, on the outer face of the hopper, above the cartridge-outlet and in proper relationship to the inclined channel b^5 of the stationary center, a curved projection, m which extends 85 a distance into the open side of the pan, as clearly shown in Figs. 12 and 13. This rib is curved to a radius rather less than that of the pan (see Fig. 13) while its edge m^2 (see Fig. 12) is inclined to a pitch corresponding 90 to the pitch of the transposing incline b^5 ; the disposition of the said rib in relation to the magazine center-block, (which, as has already been described, is locked on the supporting post in the definite position shown 95 in Fig. 13) being such that when the pan has completed about three-quarters of its first 100 rotation the base ends of all the cartridges required for making up the layers at the closed or top side of the said pan are constrained to successively wipe under or down the edge of this projecting rib at the same time that their bullet ends are being carried down the inclined transposing channel b^5 ; the result being that the base ends of the said 105 cartridges are compelled to follow the same transposing movement as their bullet ends.

To prevent cartridges dropping out of that part of the open side of the pan which projects beyond the hopper, the side of the 110 latter carries a curved guard n , which lies around the said portion of the pan (see Figs. 5 and 7) and keeps the bases of the cartridges in engagement with the retaining plates of the magazine.

The upper part of the cartridge guide of the hopper may be so constructed as to admit of loose cartridges being fed singly into the open top thereof, but, in the machine shown in the drawings, the cartridge guide 120 is provided with mechanism for stripping clipped cartridges from their clips into the said guide (down which they proceed by gravity into the hopper) and automatically ejecting the empty clips. This mechanism 125 is of the kind described in the specification of my concurrent application for Letters Patent, Serial Number 226,668, filed March 24, 1918.

As is best shown in Figs. 4 and 6, the 130

feed-guide has an aperture σ cut in its closed side, large enough to provide for the introduction of a clip of cartridges laterally therethrough the opposite sides of the bottom end 5 of this aperture being formed with a pair of suitably-curved abutments σ^2 on which the bottom corners of the clip take their bearing (see Fig. 4), when the cartridges are being stripped therefrom, while the bearings of 10 the opposite edges of the clip take a bearing against the outside of the guide, on the opposite sides of the aperture σ . Within the upper end of the said feed-guide (i. e. the part above the aperture σ) there is fitted a 15 spring-influenced catch σ^3 which primarily functions as a clip-ejector and may normally be so positioned by its spring σ^4 that it engages with an upper corner of the clip bearing during the stripping operation.

20 Thus, when a clip of cartridges is introduced laterally into the aperture and pushed over as far as it will go so that the cartridge heads come above or register with the groove in the said guide, the upper part of a bearing 25 on the said clip is engaged by the lower extremity of the clip ejector.

For mechanically stripping the cartridges from the clip into the part of the guide that leads to the hopper, the top of the said 30 guide is fitted with a depressible plunger p that, on being forced down by hand, thrusts the said cartridges clear of the arrested clip and into the feed-guide, after which the said plunger is restored to its normal position by 35 its spring p^2 .

The clip ejector is provided with an extension c^5 which comes within the path of the head p^3 of the plunger so that, when the said plunger reaches the limit of its down- 40 ward movement and all the cartridges have been stripped out of the clip, the said head will impinge on the extension c^5 of the ejector, and impart to the latter, an angular movement which trips the empty clip off its 45 seating in the feed-guide and ejects the same through the aperture σ ; the spring of the said catch subsequently returning the same to its normal position to enable another clip of cartridges to be introduced.

50 It is to be understood that the scope of the present invention is not limited to a machine in which the various mechanical and other parts are constructed and arranged precisely as above described, with reference 55 to the drawings. On the contrary, the scope of the invention includes any construction or arrangement of machine for filling Lewis magazines in which a positively-acting cartridge-feed device for thrusting cartridges 60 sidewise from a hopper is operatively combined or associated with a magazine-feed pawl or equivalent device which is adapted to directly engage the magazine pan for intermittently rotating the said pan around 65 its stationary center, while for the purpose

of obviating feed "blanks" or spaces, the cartridge-feed and magazine-feed devices may be controlled by any suitable arrangement of automatic stop mechanism which comes into action to prevent the pan-feed device 70 operating in the event of failure of the cartridge feed.

Having thus described my invention what I claim as new and desire to secure by Letters Patent is:—

75

1. In a machine for filling gun magazines of the character described, the combination with a revoluble magazine pan, of means for alternately feeding cartridges sidewise into the magazine, and rotating the pan, said 80 means comprising two independently-acting devices, and a common operating mechanism for driving both of said devices.

2. In a machine for filling gun magazines, the combination with a hopper having an 85 outlet, and a revoluble magazine pan, said magazine pan being supported in a plane perpendicular to the hopper outlet, of means for rotating the magazine pan, and a cartridge feed device adapted to thrust or force 90 cartridges sidewise from the hopper into the magazine.

3. In a machine for filling gun magazines of the character described, the combination with a revoluble magazine pan, of means for 95 alternately feeding cartridges sidewise into the magazine, and rotating the pan, said means comprising two independently-acting devices, and a common operating mechanism for driving both of said devices, said magazine 100 feeding means directly engaging the magazine pan.

4. In a machine for filling gun magazines of the character described, the combination with a revoluble magazine pan, of means for 105 alternately feeding cartridges sidewise into the magazine, and rotating the pan, said means comprising two independently-acting devices, a common operating mechanism for driving both of said devices, and means for 110 preventing "blanks" in filling, said last-named means comprising an automatic stop-mechanism controlling both the cartridge-feed and the rotation of the magazine pan, and adapted to prevent the rotation of the 115 magazine pan until the cartridge feed has introduced a cartridge into the magazine.

5. In a machine for filling gun magazines of the character described, the combination with a revoluble magazine pan, of means for 120 alternately feeding cartridges sidewise into the magazine, and rotating the pan, said means comprising two independently-acting devices, a common operating mechanism for driving both of said devices, and an automatic stop-mechanism controlling both the cartridge-feed and the rotation of the magazine pan, said stop-mechanism being controlled by the cartridge weight and permitting the machine to function normally 125 130

so long as cartridges continue to position themselves in the path of the cartridge-feed device, and said mechanism adapted to stop the operation of the machine in the event of 5 a cartridge failing to so position itself.

6. In a machine for filling gun magazines of the character described, the combination with a revoluble magazine pan, of means for alternately feeding cartridges sidewise into 10 the magazine, and rotating the pan, said means comprising two independently-acting devices, a common operating mechanism for driving both of said devices, and a stop-pawl associated with the magazine pan and 15 arranged to directly engage the pan and arrest and hold the same during the cartridge-inserting action of the cartridge-feeding means.

7. A magazine filling machine, having a 20 revoluble magazine pan; means for feeding cartridges sidewise into the magazine; alternately operating devices for actuating the pan and the cartridge-feeding means, said pan having external recesses in its rim; a 25 magazine feed device engaging said pan; and a stop-pawl engaging the pan and adapted to arrest and hold the same during the cartridge inserting action of the cartridge feeding means, said magazine feed 30 device and stop-pawl adapted to directly engage the external recesses of the pan.

8. In a machine for filling gun magazines of the character described, the combination with a revoluble magazine pan, of means for 35 alternately feeding cartridges sidewise into the pan, and rotating the pan, said means comprising two independently-acting devices, a common operating mechanism for driving both of said devices, a hopper having an outlet formed horizontally in its side, 40 said pan being supported in a plane perpendicular to the hopper outlet; and a magazine supporting post located by the side of the bullet-end of the outlet of said hopper.

45 9. In a machine for filling gun magazines of the character described, the combination with a revoluble magazine pan, of means for alternately feeding cartridges sidewise in the magazine, and rotating the pan, two independently-acting devices for rotating the 50 pan and actuating the cartridge feed, a rotary crank for operating said devices, and a spring-actuated clutch interposed between the crank and said devices and controlling 55 the latter.

60 10. In a machine for filling gun magazines of the character described, the combination with a revoluble magazine pan, means for alternately feeding cartridges sidewise into the magazine and rotating the pan, said means comprising two independently-acting devices and a common operating mechanism 65 for driving both of said devices, a hopper having an outlet adapted to guide cartridges at a point at which they are transferred side-

wise into the magazine, a reciprocating cartridge-feed plunger, and a rotary driving element for actuating the plunger.

11. In a machine for filling gun magazines of the character described, the combination 70 with a revoluble magazine pan, means for alternately feeding cartridges sidewise into the magazine and rotating the pan, said means comprising two independently-acting devices and a common operating mechanism 75 for driving both of said devices, a hopper having an outlet adapted to guide cartridges at a point at which they are transferred sidewise into the magazine, a reciprocating cartridge-feeding plunger, and a rotary driving element for actuating the plunger.

12. In a machine for filling gun magazines of the character described, the combination 80 with a revoluble magazine pan, means for alternately feeding cartridges sidewise into the magazine and rotating the pan, said means comprising two independently-acting devices and a common operating mechanism 85 for driving both of said devices, a hopper having an outlet adapted to guide cartridges at a point at which they are transferred sidewise into the magazine, a reciprocating cartridge-feed plunger, and a rotary driving element for actuating the plunger, 90 said plunger being provided with a lifting attachment that operates during the feeding stroke of the plunger, to relieve the bottom cartridge in the hopper of the weight of the other and superimposed cartridges and 95 keeps the cartridges free in said hopper.

13. In a machine for filling gun magazines of the character described, the combination with a revoluble magazine pan, means for alternately feeding cartridges 100 sidewise into the magazine and rotating the pan, said means comprising two independently-acting devices and a common operating mechanism for driving both of said devices, a hopper having an outlet adapted to 105 guide cartridges at a point at which they are transferred sidewise into the magazine, a reciprocating cartridge-feed plunger and a rotary driving element for actuating the plunger, and a spring device for exerting 110 endwise pressure against each cartridge as it falls in front of the feed plunger.

14. In a machine for filling gun magazines of the character described, the combination with a revoluble magazine pan, means 115 for alternately feeding cartridges sidewise into the magazine and rotating the pan, said means comprising two independently-acting devices and a common operating mechanism for driving both of said devices, a hopper 120 having an outlet adapted to guide cartridges at a point at which they are transferred sidewise into the magazine, a reciprocating cartridge-feed plunger and a rotary driving element for actuating the plunger, and an 125

oscillating magazine-feed pawl geared to said crank and directly engaging the pan and adapted to intermittently rotate said pan in the counter-clockwise direction, said 5 pawl being timed to operate during the return stroke of the cartridge feed plunger.

15. In a machine for filling gun magazines of the character described, the combination with a revoluble magazine pan, means 10 for alternately feeding cartridges sidewise into the magazine and rotating the pan, said means comprising two independently-acting devices and a common operating mechanism for driving both of said devices, a hopper 15 having an outlet adapted to guide cartridges at a point at which they are transferred sidewise into the magazine, a reciprocating cartridge-feed plunger and a rotary driving element for actuating the plunger, a stop- 20 pawl adapted to directly engage the pan for arresting and holding the same during the cartridge inserting action of the cartridge-feeding device, a spring for holding said pawl up to its work, and a cam-formation on 25 the pivot end of said stop-pawl, the arrangement being such that when the stop-pawl is turned over or disengaged, from the maga-

zine the pressure which its cam normally exerts on the feed-device spring is relieved.

16. In a machine for filling gun magazines 30 of the character described, the combination with a revoluble magazine pan, of means for alternately feeding cartridges sidewise into the magazine and rotating the pan, said means comprising two independently-acting 35 devices and a common operating mechanism therefor, a stop-pawl adapted to directly engage the pan for arresting the same during the cartridge inserting action of the cartridge feed device, an adjustable spindle on 40 which the stop-pawl is mounted, and a magazine catch or retaining device carried by said spindle, the arrangement providing for the adaptation of the machine to accommodate the magazines of different cartridge 45 capacities.

In testimony whereof I have hereunto set my hand in presence of two subscribing witnesses.

HARRY ROBERT NORTHOVER.
